UNITED STATES PATENT OFFICE.

WILLIAM CHESTERMAN, OF SHEFFIELD, ENGLAND.

TAPE-MEASURE.

No. 898,320.

Specification of Letters Patent.

Patented Sept. 8, 1908.

Application filed July 30, 1906. Serial No. 328,294.

To all whom it may concern:

Be it known that I, WILLIAM CHESTERMAN, a subject of the King of Great Britain and Ireland, residing at Bow Works, Sheffield, in the county of York, England, manufacturer, have invented certain new and useful Improvements in or Relating to Tape-Measures, of which the following is a specification.

10 This invention relates to tape measures, and consists in improvements of the means shown in the specification to British Patent No. 5382/1886 of securing the inner end of the tape to the central boss or spindle on 15 which it is wound with the object of facilitating its attachment thereto.

The means by which this is attained is shown in two forms which are illustrated in Figures 1 to 4 and Figs. 5 to 7 respectively of 20 the accompanying drawings, Fig. 1 being a diametrical section of one form of the improved tape measure; Fig. 2 is a side elevation, and Fig. 3 an end elevation of the combined boss and axle pin, and Fig. 4 a side elevation of the same with the device for facilitating assembly attached thereto; Fig. 5 is a view corresponding with Fig. 1 showing a modified construction, and Figs. 6 and 7 detail views thereof corresponding with those 30 of Figs. 2 and 3 with the handle folded into the inclosed position.

In Figs. 1 and 5, the winding handle is shown in a position for winding purposes, while in Figs. 2, 3, 4, 6 and 7 this handle is 35 shown as folded back into a closed or inoperative position.

In the former construction the boss or sleeve *a* which acts as the winding drum for the tape *b* and the axle pin *c* are formed 40 in one piece, and the latter is threaded through the loop *b'* at the inner end of the tape which leads out through the longitudinal slot *a'* in the boss *a*. To facilitate the insertion of the pin *c* in the loop, the end of 45 the pin which is hollow and screw-threaded for the reception of the retaining set screw *d* in the usual manner, has temporarily screwed into it a taper pin *e* which is passed approximately centrally within the casing, 50 and the boss *a* is then turned until the slot *a'* slips over the edge of the tape. The pin *e* is then unscrewed, and the eyelet washer *f* and retaining screw *d* placed in position as shown in Fig. 1.

55 In the construction of Figs. 5, 6 and 7, *h* and *k* are portions of the winding axle to

which is hinged the winding handle *l*, the axle-pin *c* is of non-circular section and may be squared or flattened as at *c'*, and the slotted sleeve *a* which is of an internal diameter very 60 slightly larger than *c* and similarly squared or flattened is detachable. In this case the end of the tape *b* is passed into the casing and out through the central hole in the casing which is afterwards closed by the cheek of 65 the winding axle as soon as the several elements have been assembled and the tape measure is ready for use. It is then given a turn round the flattened axle pin which during this operation is held below said central 70 hole and the flattened sleeve slipped or sprung over it from the set screw end of the axle pin, thereby clipping the end of the tape on the pin as shown in Fig. 7, after which the whole is placed in position and secured as 75 shown in Fig. 5.

Having thus described the nature of my 80 said invention, and the best means I know of carrying the same into practical effect, I claim:—

1. In measuring tapes, means for attaching the inner end of the tape to the winding axle comprising a central axle pin, a sleeve surrounding the said axle pin and having a longitudinal slot, and means facilitating the 85 insertion of the axle pin through the inner looped end of the tape, substantially as described.

2. In a measuring tape, the combination of a central axle pin around which the end of 90 the tape is looped, a winding handle hinged to said axle pin, and a sleeve having a longitudinal slot, said sleeve adapted to receive said end of tape around the axle pin and to operate as the winding drum; substantially 95 as described.

3. In a measuring tape, the combination of a central axle pin having a flat portion around which the end of the tape is passed, a winding handle hinged to said axle pin, a 100 detachable slotted sleeve having a flat portion and adapted to engage over said axle pin, and end of the tape, thereby clamping the latter, substantially as described.

In testimony whereof, I have signed my 105 name to this specification in the presence of two subscribing witnesses.

WILLIAM CHESTERMAN.
